MUFFLER WITH EXPANSION CHAMBER DEFINING CENTRIFUGAL FLOW PATH Ramon B. Hill, 12415 SW. 186th St.,
Miami, Fla. 33157Filed July 22, 1964, Ser. No. 384,397
5 Claims. (Cl. 181—58)

This invention relates to improvements in mufflers for exhaust gases. It is particularly useful as a muffler for exhaust gases from internal combustion engines of heavy trucks and tractors, but is not limited to such use.

It is customary for exhaust gases from engines of trucks and tractors to be passed from the engine through an elongated muffler and thence through a substantially vertical exhaust pipe to the atmosphere. The exhaust gases normally pass through an exhaust pipe connecting a muffler inlet to an exhaust manifold of the engine. This exhaust pipe usually includes at least one elbow or substantially right angle bend. The muffler is provided with an outlet which is ordinarily in substantially the same horizontal plane as the inlet, and another elbow or substantially right angle bend in the tail pipe is provided to direct the tail pipe upward. The mufflers used usually are cylindrical or oval in cross section and are provided with internal baffles, usually perforated, and so arranged that the exhaust gases pass through a plural number of expansion stages before discharge from a substantially central location in an end of the muffler opposite the inlet.

This arrangement is often disadvantageous from the standpoint of space requirements. The presence of elbows or sharp bends in the path of hot gases also results in increasing back pressure and in concentrating the corrosive and erosive effects of the gases at such elbows or bends. Frequent failure of elbows or bends is so common that replacement of elbows is a large item of upkeep expense with most companies engaged in highway trucking operations. Elbows and direct baffling also increase back pressure on the exhaust gases; and tend to decrease the useful life of the muffler.

It is an object of this invention to provide a muffler which does not require exhaust pipes or tail pipes containing elbows or sharp bends.

Another object is to provide a muffler in which a change in direction of exhaust gases occurs gradually during expansion of the gases in a chamber of large volume. Another object is to provide a muffler which applies little back pressure on exhaust gases.

Another object is to provide a muffler in which a large part of the muffling function is performed by streams of exhaust gases impinging upon each other.

Another object is to provide a muffler which has high muffling effect in a small volume.

Another object is to provide a muffler which has very long useful life.

Other objects and advantages and features of this invention will be apparent to one skilled in the art upon a consideration of the written specification, the attached claims and the annexed drawing.

The muffler of the present invention includes a shell which preferably is elliptical in cross section although it may have other cross sectional shapes as for example, circular or rectangular with the corners rounded. An elliptical cross section is preferred because it gives the greatest muffling power in the smallest volume. The shell preferably includes a substantially vertical side wall which may be straight or curved in vertical elevation and a pair of end closure members, preferably domed, cooperating with the side wall to close the shell.

The vertical side wall has a horizontally elongated inlet opening which extends for a major part of the length

2

of the muffler, i.e., of the ellipse defined by the side wall, and the inlet opening is parallel thereto. An inlet conduit for exhaust gases extends horizontally along the side opening in gas-type contact with the wall of the shell surrounding the opening. The conduit has an elongated lateral outlet opening and registering with the inlet opening and preferably has an inner end substantially tangent to the side wall when the side wall is elliptical, or at a very small angle to the side wall if the side wall is of rectilinear shape. An outer end of the conduit is adapted to be connected to an exhaust pipe from an internal combustion motor and may be slightly enlarged and slotted to make a slip fit upon the end of such exhaust pipe, or may then have any other type of connecting means desired.

Perforate baffles are disposed vertically in the shell providing a baffled zone in the shell opposite the inlet and at a level of the inlet opening. These baffles do not extend vertically all the way across the shell but provide a completely unbaffled zone extending across the shell below the baffles.

These baffles are usually two or three in number depending upon the size of the muffler. When three are used the first baffle preferably extends across the muffler from a point adjacent the end of the inlet opening to an opposite wall. This baffle may be flat or arched outward toward the midpoint of the muffler as desired. The second baffle extends from the junction point of the first baffle with the side wall opposite the inlet, is arched outward toward the longitudinal centerline of the muffler and extends to a second point on the wall opposite the inlet opening so that the baffles are of approximately the same length. The third baffle extends from the second point on the side wall of the muffler to a tail pipe conduit at a point on the conduit approximately in the centerline of the muffler.

The tail pipe conduit extends vertically downward through an upper end of the muffler at a location substantially at the focus of the ellipse defined by the side wall nearest the beginning of the inlet opening. The tail pipe conduit extends downward through the baffle zone to the level of the bottom of the baffles where it communicates through its open end with the unbaffled zone extending across the muffler.

It will be seen that with this arrangement a stream of hot high velocity exhaust gases entering through the exhaust pipe conduit will begin to expand, cool and slow down at different rates after they reach the beginning of the inlet opening. If different parts of this stream be considered as laminae it will be seen that the direction of expansion of the laminae also is different. Gas traveling at high velocity along the wall of the connector nearest the shell expands outward into the shell immediately when it arrives to the beginning of the inlet opening through the side wall, while the laminae more and more remote from the shell continue onward at high velocity until they arrive at a location further from the initial edge of the inlet opening until the last gases are discharged from the connector in a direction substantially tangent to the ellipse defined by this said wall.

As a result the gases within the shell are given a swirling motion around the interior of the elliptical shell but the swirling motion is highly turbulent. The swirling turbulent gases are further broken up and turbulence is increased by contact with the perforated baffles. That part of the gas which passes through perforations in the first two baffles is directed downward into the unbaffled space. It will be seen also that there is expansion of exhaust gases downward in the muffler so that a part of the stream does not reach the baffle at all but passes

directly downward into the unbaffled space and flows upward through the tail pipe conduit from that location.

A part of the gases passing through perforations in the third baffle also expand downward into the unbaffled space while other parts pass through lateral openings in the tail pipe conduit within the baffled zone in the form of jets entering at substantially right angles to the direction of flow of the stream gases entering the open bottom of the tail pipe conduit communicating with the unbaffled zone. A portion of the stream gases entering the inlet also passes directly to the lateral openings in the tail pipe conduit so that a very high degree of turbulence is present within the tail pipe conduit and much of the controlled expansion of exhaust gases is due to the high degree of turbulence within the tail pipe conduit.

Controlled expansion, cooling, and change direction of the gases thus occurs without the use of direct baffling of all gases. No points are present in the muffler where there is a sharp change in direction of high velocity hot gases, and thus there is no concentration of corrosive and erosive effects.

The muffler may, if desired, have more than one inlet opening on the same side or on opposite sides of the shell, and tail pipe conduits extending through both ends of the shell. When multiple inlets are used, and are located at different levels in the muffler, separate series of baffles are arranged to provide separate baffled zones at the level of each inlet. It is preferred that a single, central, unbaffled zone extending across the central section of the muffler between the bottom and to edges of upper and lower series of baffles be provided. In this arrangement separate tail pipe conduits extend through opposite ends of the shell, through the corresponding baffled zone to the central unbaffled zone.

This arrangement is substantially the same as two single inlet mufflers placed end to end with separating end closure members omitted. It is particularly useful when more than one exhaust manifold is present, as for example, in a V-8 engine.

The construction of the muffler of the present invention can be best appreciated by reference to a detailed description of one preferred type of muffler shown in the attached drawings wherein:

FIG. 1 shows one preferred muffler constructed according to principles of this invention illustrating partially in horizontal cross section, a highly effective arrangement of inlet conduit, shell, baffle, and tail pipe;

FIG. 2 is a vertical section through the muffler of FIG. 1 on the line 2-2;

FIG. 3 is a perspective view of the same muffler on reduced scale.

Since it is necessary to orientate elements of the improved muffler with respect to each other for convenience in the description, the terms "vertical," "horizontal," "lateral," "above" and "below" are used in describing the muffler of the present invention in a special restricted sense in this specification and claims, to mean the corresponding directions and relationships as illustrated in FIG. 2 of the drawings, although it is to be understood that the muffler may be installed at any angle.

In the drawings the reference numeral 5 designates generally a shell which preferably is of elliptical shape in cross section. As illustrated the shell includes a vertical side wall 6 defining an ellipse 7, and closure members 8 and 9 cooperative with the side wall to close the shell. The side wall 6 has a horizontally elongate opening 11 therethrough which serves as an inlet for exhaust gases into the shell.

A curved inlet conduit for exhaust gases 12 extends horizontally along one side of the shell in gas tight contact with the wall of the shell surrounding the opening. The conduit has a lateral elongate outlet opening registering with the inlet opening 11. The inner end 13 of the inlet conduit preferably is substantially tangent to shell 6 and the elongate opening 11 and the matching

opening in conduit 12 are of such length as to extend for a major part for the length of ellipse 7.

Within the shell a plurality of perforated vertical baffles are disposed to provide a baffled zone within the shell at the level of the inlet opening. In the preferred arrangement of baffles shown, three baffles 14, 15 and 16 are used. The baffle 14 extends from a point within the shell adjacent to the tangent end 13 of inlet conduit 12 and is arched across the baffle to a point 17 on the wall 6 where it joins a second baffle 15 arched inward from point 17 to point 18 on the wall of the shell. The baffle 16 extends from point 18 to a tail pipe 19. It is preferred that these baffles be of approximately equal size and length.

Baffles 14, 15 and 16 extend vertically from a point adjacent to the upper level of side wall 6 downward to provide a large unbaffled zone extending all the way across the interior of the shell at a level below the lower edges of the baffles. The unbaffled, unobstructed zone is of substantial size, as for example, approximately $\frac{1}{3}$ the total volume of the shell. The tail pipe 19 extends vertically through end member 8 through the baffled zone 21 to the unbaffled zone 22. Pipe 19 has an open lower end 23 communicating with zone 22 and has numerous lateral openings 24 communicating with the baffled zone 21.

The tail pipe conduit has a suitable connection 25 adapted to be connected to a vertical tail pipe 26 extending upward to discharge exhaust gases into the atmosphere. The inlet conduit 12 also has an end remote from the shell 5 illustrated as an enlarged and slit end 27, adapted to be connected with an exhaust pipe 28.

In operation a stream of exhaust gases, as for example, from an internal combustion engine is introduced through exhaust pipe 28 into the inlet conduit 12 at high velocity. The inlet opening into the shell is very long and is in register with an elongate outlet from exhaust pipe 12 so that the high velocity gases begin to expand outward when they reach the point 29. Some of the gas immediately begins to expand laterally into the shell into the direction indicated by the arrow 30 while other portions of the gas continue onward in the direction indicated by the arrows 31 and 32. Ultimately all the gas entering through inlet conduit 12 and passing in the direction shown at 31 and 32 moves outward as shown by the arrows 33 and 34 in the shell.

A large portion of the gases thus are discharged toward the baffles 14, 15 and 16, but since the distance between the inlet opening and baffles is substantial, entering gases, also expand downward into this unbaffled space below the baffles. Gases passing through perforations in baffles 14 and 15 also move downward into the unobstructed space below the baffles.

As the high velocity gases move outward into the shell they begin to expand, to cool and to slow down at different rates, and directions of expansion are different after they have reached the point 30. By the time the gases from inlet conduit 12 have reached point 35 they have begun to curve due to the curvature of inlet conduit 12 and as they whirl around the interior of the elliptical shell they are broken up by passing through and over the perforated baffles. In order for these whirling gases to be expelled through the outlet they must go either through the openings 24 into tail pipe conduit 19 or downward into the unobstructed zone 22 and upward through the open bottom of conduit 19. The proportion of gases taking these ultimate paths obviously will be dependent upon the resistance offered by the two paths. A large proportion of the gas will pass downward into space 22 and upward through conduit 19 where it encounters jets of exhaust gas entering through openings 24 at substantially right angles to the flow of gases within conduit 19. Impingement of jets entering through openings 24 upon the stream of gas flowing upward in tail pipe conduit 19 results in turbulence, and a great deal of the muffling func-

tion is performed by turbulence of the gases. There is no sharp change in direction of an entire stream of hot gases flowing at high velocity at any point within the muffler. Expansion takes place gradually and is accompanied by cooling by simultaneous change of flow. The change in direction is gradual rather than sharp and no direct baffling occurs. As a result mufflers of this type have a very long useful life and are free from the disadvantages due to high back pressure caused by direct baffling.

From the foregoing, it will be seen that this invention is one well adapted to attain all of the ends and objects hereinabove set forth, together with other advantages which are obvious and which are inherent to the apparatus.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. A muffler comprising in combination a vertical shell having a horizontally elongate inlet opening in a side thereof for a distance equivalent to a major part of the length of the muffler; an inlet conduit for exhaust gases extending horizontally along said opening in gas-tight contact with the wall of said shell surrounding said opening, said conduit having a lateral elongate outlet opening registering with said inlet opening; perforate baffles disposed vertically in the shell providing a baffled zone in said shell at the level of said openings and an unbaffled zone extending across the interior of the shell below said baffles; and a tail pipe conduit extending vertically through an end of the shell, through said baffled zone to said unbaffled zone at a location near an end of the shell nearest an initial end of said inlet opening and on a centerline of the shell, said tail pipe conduit having an open inner end communicating with the unbaffled zone and numerous lateral openings communicating with said baffled zone.

2. A muffler comprising in combination a vertical shell substantially elliptical in horizontal cross section having a horizontal elongate opening in a side thereof extending for the major part of the length of an ellipse defined by the sidewall; an inlet conduit extending horizontally along said opening in gas tight contact with the wall of said shell surrounding said opening, said conduit having an elongate lateral outlet opening registering with said inlet opening; perforate baffles disposed vertically in the shell providing a baffled zone in said shell at the level of said openings and an unbaffled zone extending across said

shell below said baffles; and a tail pipe conduit extending vertically through an end of the shell substantially at a focus of the ellipse nearest an initial end of said inlet opening extending through the said baffled zone to said unbaffled zone, said tail pipe having an open inner end communicating with the unbaffled zone and numerous lateral openings communicating with said baffled zone.

3. A muffler comprising in combination a vertical shell having a horizontally elongate inlet opening in a side thereof extending for a major part of the length of said shell; an inlet conduit for exhaust gases extending horizontally along said opening in gas tight contact with the walls of said shell surrounding said opening, said conduit having an elongate opening registering with said inlet opening; perforate baffles disposed vertically in the shell providing a baffled zone in said shell at the level of said openings and an unbaffled zone extending across the shell below said baffles, said unbaffled zone having a volume approximately $\frac{1}{3}$ the total volume of said muffler; and a tail pipe extending vertically through an end of the shell, and through said baffled zone to the unbaffled zone at a location on the centerline of the shell and near an end of the shell, said tail pipe having an open end communicating with the unbaffled zone and numerous lateral openings communicating with said baffled zone.

4. The muffler of claim 3 in which the baffles extend downward from a level adjacent the top of the side wall of the shell and a first baffle extends from a point on the interior of the shell adjacent to an inner end of the inlet opening to a point on the shell across from said inlet, and another baffle extends from a point on the shell across from the inlet to the tail pipe conduit at a point thereon substantially on the longitudinal centerline of the shell.

5. The muffler of claim 4 having three baffles of approximately equal length, namely a first baffle extending from a point on the interior of the shell adjacent to an inner end of the inlet opening to a first point on the shell across from said inlet; a second baffle arched toward the centerline of the shell extending from said first point to a second point on the shell across from said inlet, and a third baffle extending from said second point to a point on the tail pipe conduit adjacent the centerline of the shell.
